PLASTIC CAP FOR ATTACHMENT OF SNAP
FASTENER SOCKETS AND THE LIKEWalter I. Jones, Belmont, Mass., assignor to
United-Carr Fastener Corporation, Cambridge,
Mass., a corporation of Massachusetts

Application July 26, 1947, Serial No. 763,861

5 Claims. (Cl. 24—216)

1

This invention relates to improvements in fasteners of the type generally used on flexible materials such as clothing, leather goods and the like and in the specific disclosure is directed particularly to a socket member constructed to provide a socket piece having a yieldable stud-engaging entrance surrounded by a flange on one side of the material to which the member is to be attached and a cap part on the other side of the material operating to fasten the cap part to the socket piece and to the material.

The cap part, which is the main subject of my present application, is distinguishable from known cap members by providing a part formed of plastic material. This plastic construction presents several advantages over metal materials previously used in that it not only permits unlimited opportunity for use of novel and attractive colors and designs on the exterior of the carrying material as distinguished from the more limited effects provided by metal caps, but also results in certain new and useful mechanical improvements not before known.

Thus having reference to the accompanying drawing and the detailed description of the invention as set out in the specification below, it will be seen that the cap member, as a result of the flexible characteristics of its plastic construction, is capable of expansion and contraction with the socket piece during engagement of a stud head with the socket piece thereby permitting a smooth and natural fastener action which eliminates the danger of so-called "setting" of the socket piece, a failure often effected in the former metal cap assemblies. Also, the plastic cap is constructed in a novel way to provide a sufficient thickness of material at its closed top portion to allow the stud-engaging sections of the socket piece to be expanded within the cap by end pressure against the cap top portion without bulging or disfiguring the outer surface of the top portion, and at the same time, to have an inwardly extending wall on the under side of the cap of less thickness than the top permitting the wall to yield with the flexible stud-engaging sections of the socket piece during engagement of a stud therewith.

Another advantage is the fact that I provide a one-piece plastic cap without metal support as against previous caps which were assemblies of sheet plastic with one or more metal pieces. Also my improved cap retains its color with wear, whereas painted metal caps wear down to the metal quite rapidly and become unsightly.

2

Referring to the drawing in which I have illustrated a preferred embodiment of my invention:

Fig. 1 is a sectional view of the cap part of my improved cap part showing the form in which it is preferably originally molded;

Fig. 2 is a sectional view similar to Fig. 1, but showing the cap part after a secondary operation to form a cavity to receive a socket piece;

Fig. 3 is a bottom plan view of the cap part shown in Fig. 2;

Fig. 4 is a view partly in section representing the cap material and socket piece in position prior to being secured in attached assembly;

Fig. 5 is a view similar to Fig. 4 with the parts in attached assembly with the carrying material, and

Fig. 6 is a bottom plan view of the assembly shown in Fig. 6.

Referring to my preferred form of fastener member most clearly illustrated in Figs. 4 and 5 of the drawing, I have shown a socket piece 1 which may be of well-known construction secured in attached relation to a piece of supporting material 2 by means of a novel cap part 3. The cap part 3 is made of plastic material initially formed in a mold into the shape shown in Fig. 1 wherein the cap provides a top portion 4 and an annular wall portion 5 extending beneath the top portion 4 in substantially normal relation to the general plane of the top portion. It will be noted that the top portion 4 has a thickness which is greater than the wall portion 5 for purposes to be described more fully hereinbelow. Prior to assembly of the parts of the fastener member the cap 3 is subjected to a secondary operation wherein by pressure and preferably the employment of heat, the annular wall 5 is pressed inwardly so that portions of the same underlie the inner surface 6 of the top portion 4 to form a divergent walled cavity 7. The lower ends 8 of the wall 5 define an entrance 9 into the cavity 7 for a purpose to be described.

The socket piece 1 in initial tubular shape illustrated in Fig. 4, comprises a number of flexible sections 10 which are connected at one end by a connecting portion 11. The sections 10 define at their other end a yielding stud-receiving entrance 12, and each of the sections 10 has a laterally extending flange element 13 adjacent the stud-receiving entrance. When the parts of the fastener are in final secured assembly with the support 2, the side edges 14 of the flange elements 13 substantially abut to form a substantially con-

tinuous flange as shown in Fig. 6. Other well known types of sockets may be used as will be understood by those skilled in the art.

To secure the socket piece in assembly with the support, the socket piece is mounted in a die (not shown) and the sections 10 are extended through an opening 15 in a support 2, as shown in Fig. 4. The cap part 3 is also secured in a die (not shown) and as one die is moved toward the other, the connecting portion 11 of the socket piece is forced against the inner surface 6 of the top portion 4 of the cap 3. As pressure is continued, the sections 10 of the socket piece are transformed from their generally tubular shape, shown in Fig. 4, into their finished or bulged shape, shown in Fig. 5 due to the presence of a circumferentially weakened area 17 adjacent the closed end 11, as by reducing the width of the segments 10. As the sections, as a result of the end pressure applied by the socket piece and cap moving into abutment, are bent or folded outwardly a flange is formed upon one side of the supporting material 2 and a stud-receiving enlargement is established within the cavity 7 of the cap part 3. It is apparent that the inner surface 6 of the top part 4 of the cap operates substantially as an anvil during the action by which the sections 10 of the socket piece are folded outwardly. The pressure of the socket piece against the top 4 during this action is such that unless the top part 4 of the cap part is formed of sufficient thickness, the top part will be deformed or pressed outwardly with the result that an unattractive bulge or protuberance will be formed on the outer visible surface of the cap part. Consequently, in my preferred device I desire to have the top portion 4 of sufficient thickness to withstand the end forces exerted upon it during collapsing of the socket piece.

It will thus be seen that when the socket piece is in final collapsing attachment within the cavity 7 of the cap part that the yielding sections 10 of the socket piece lap upon the inner surface 16 of the wall 5, as most clearly shown in Fig. 5, and preferably substantially follow the contour of the inner surfaces of the top portion 4 and wall 5 which define the cavity 7. By this development the cap is locked to the socket piece and also to the material. The stud-receiving entrance 12 of the socket piece is normally of smaller diameter than a cooperating stud head (not shown) with the result that passage of the stud head through the entrance causes the yieldable sections 10 to expand and after the stud head has been moved a predetermined distance through the entrance to contract and resiliently engage the stud head in a manner well known to those skilled in the art. In fastener members of known construction wherein the cap part was formed of metal, the metal wall corresponding to the wall 5 was incapable of expansion and contraction with the flexible sections of the socket piece with the result that the sections had a tendency to set in expanded positions thereby varying the resiliency of the socket piece. With the plastic cap part to which my preferred invention is directed the inherent resiliency of the wall portion 5, which is formed of predetermined thickness to insure such resiliency, permits the wall portion, which in my preferred form is in abutting engagement with the yieldable sections 10, to flex outwardly with the sections 10 during expansion of the sections while the stud is being moved into engagement therewith and to contract with the sections 10 as they engage the

stud head. This inherent flexibility of the plastic wall 5 permits a uniform and continuous flexibility of the socket piece with the result that the fastener action remains constant after repeated engagement and disengagement of the stud and socket member.

Thus I have provided a simple, inexpensive cap part that has many uses and will replace more expensive assemblies.

While I have illustrated and described a preferred embodiment of my invention, I do not wish to be limited thereby because the scope of my invention is best defined by the following claims.

I claim:

1. An attaching cap for assembling a snap fastener part to a support, said cap being formed of plastic material and providing a one piece structure free of any metal part and having a top portion and an inwardly extending resilient slanting wall under said top portion and terminating at a metal free opening to provide an expandible divergent walled cavity to receive a portion of the snap fastener part when expanded within said cap.

2. A cap member adapted to serve as a covering and as a means for attaching a sheet metal snap fastener part to a supporting material, consisting of a cup-shaped one-piece metal-free body of moldable plastic material having a top portion and an inwardly converging peripheral resilient flange providing a preformed divergent walled cavity within the body and within which a sheet metal fastener part may be upset and expanded into direct and intimate contact with the plastic walls of said cavity, the top portion of said body being of greater thickness than said peripheral flange to resist deformation when subjected to pressure to upset a sheet metal socket part within said cavity.

3. A snap fastener socket member consisting of a plastic cap part and a sheet metal socket fastener part, said plastic cap part having a base portion and an inwardly extending flexible wall on its under surface forming a divergent walled cavity having a reduced neck, said sheet metal socket fastener part comprising a split resilient body portion upset and expanded within said cavity to provide an expandible stud-receiving pocket, said flexible wall being capable of expansion and contraction when a stud member is moved into or out of said stud-receiving pocket.

4. A snap fastener socket member consisting of a plastic cap part and a sheet metal socket fastener part, said plastic cap part having a base portion and an inwardly extending flexible wall on its under surface forming a divergent walled cavity having a reduced neck, said sheet metal socket fastener part comprising a sheet metal shank having a plurality of separate sections upset and expanded within said cavity and said reduced neck to provide an expandible stud-receiving pocket, said flexible wall being capable of expansion and contraction when a stud member is moved into or out of said stud-receiving pocket, and an outwardly extending support-gripping flange integral with an end of said shank.

5. A snap fastener socket member consisting of a plastic cap part and a sheet metal socket fastener part, said plastic cap part having a base portion and an inwardly extending flexible wall on its under surface forming a divergent walled cavity having a reduced neck, said sheet metal socket fastener part comprising a sheet metal

shank having a closed end, an opposite open end and an intermediate body portion, said body portion having a plurality of circumferentially weakened areas, the material between said areas being upset and expanded within said cavity and said reduced neck to provide an expansible stud-receiving pocket, the top portion of said body being of sufficient thickness to resist deformation when subjected to pressure to upset a sheet metal socket part within said cavity.
